The schedule referred to in these Letters Patent and making part of the same.

Claims where it may concern:

Be it known that I, Elemir J. Rev. of Lowell, in the County of Middlesex, and State of Massachusetts, have originated and designed a new pattern for Carpets or other fabrics, of which the following is a full, clear and exact description, reference being had to the accompanying drawings making part of this Specification.

Corners 1 and 2, are quarters of plain center surrounded by branch work.

Corners 3 and 4, are quarters of center the interior of which is composed of small diamonds.

The quarters of centers 1. 3. 4, bear the set figures B, which are formed of small balls and sprig-work. Fig. C is composed of sprig work resting on center 2. Between the branches A, and centers 3 and 4 is a group of flowers and leaves D.

The colors employed for the different portions of the design may be varied to suit the taste and wish of the manufacturer.

Claims.

What I claim as my invention and desire to secure by Letters Patent, is the design or pattern for Carpets and other fabrics, herein set forth.
